UNITED STATES PATENT OFFICE.

PETER DE MATTIA AND BARTHOLD DE MATTIA, OF CLIFTON, NEW JERSEY.

CORE AND CHUCK.

Application filed August 6, 1921. Serial No. 490,393.

To all whom it may concern:

Be it known that we, PETER DE MATTIA and BARTHOLD DE MATTIA, citizens of the United States, and residents of Clifton, in the county 5 of Passaic and State of New Jersey, have invented certain new and useful Improvements in Cores and Chucks, of which the following is a full, clear, and exact description.

The present invention relates to cores and 10 chucks employed in the manufacture of pneumatic tires. In practice such cores and chucks are mounted upon a revoluble table forming part of a jack, and it is desirable that they be firmly connected to the table so 15 as to be capable of quick removal therefrom, and that the connecting devices while simple in operation, nevertheless, shall form an effective connection and one not liable to dis- arrangement while turning the core as the 20 tire is formed thereon.

To the above end the present invention consists of the devices and combinations of devices which will be hereinafter described and claimed.

25 In the drawings we have illustrated in— Fig. 1 a plan view of a combined chuck and core embodying the invention.

Fig. 2 shows a detail of the locking bolt and its operating pinion, parts being shown 30 in elevation and parts in section, the section being taken on the line 2—2 in Fig. 1.

Fig. 3 shows a detail of the locking bolt and one of the cooperating locking studs, parts being shown in elevation and parts in 35 section, the section being taken on the line 3—3 in Fig. 1.

Fig. 4 is a top plan view of the locking bolt removed.

Fig. 5 shows a sectional view taken through 40 a portion of the core and the means for operating the key section, and also the revolving table and a portion of the jack.

Fig. 6 shows a side elevation of portions 45 of the chuck and core, parts being shown in section taken on the line 6—6 of Fig. 1.

Fig. 7 shows a sectional view through the table, the chuck and other parts are taken on the line 7—7 in Fig. 1.

Similar reference characters will be em- 50 ployed to designate corresponding parts.

As shown, the core is a collapsible core comprising a fixed section 10 supported upon arms 11 and 12, forming an integral part of the chuck 13. It also comprises a swinging 55 section 14 pivotally mounted at 15 upon the arm 12, and a combined swinging and swiv-

eling section 16 pivoted at 17 to a swivel 18 which is mounted in a bearing 19 carried by the fixed section 10.

A key section 20 is pivotally connected at 21 to a sliding bar 22 which has a sliding movement in a bearing carried by the chuck, and along one edge is provided with worm teeth 23 engaged by a worm 24 mounted in a suitable bearing 25 and provided with a polygonal stem 26, which may be engaged by a suitable wrench whereby the worm may be turned to reciprocate the sliding bar 22 and thus move the key section 20 radially into and out of operative continuity with the other sections of the core.

Such a core is well-known to those skilled in this art and its construction and mode of operation need not be further described herein, and in and of itself it forms no part 75 of the present invention.

A table 27 is provided with a shaft 28 which is held to revolve in a bearing 29 at the forward end of an arm 30 of a supporting jack, and upon its under side is provided 80 with a notched flange 31 arranged to be engaged by a spring pressed bolt 321 to hold the table fixed at any point to which it may be turned.

This table and jack is also well-known to 85 those skilled in the art and need not be further described, and as so far described in and of themselves constitute no part of the present invention.

The table 27 is provided with upwardly 90 extending studs 32, which as shown in Fig. 3 are provided with a stem 33 which passes through the table 27, and which at its lower portion is threaded as at 38 and receives a threaded nut 39, the lower shouldered end 95 40 of the stud 32 resting upon the upper surface of the table 27. To prevent the studs from turning in the table, dowel pins 41 pass through the table and the shank 33. The upper ends of the studs 32 are bevelled 100 or tapered as shown at 42, and they are provided with a notch or slot 43 extending tangentially across one surface, the lower edge 44 of the notch being raised above the shoulder 40, a distance substantially equaling the 105 thickness of the chuck 13.

There are two of these studs 32 carried by the table 27 located diametrically opposite each other at equal distances from the center of the chuck, and when fixed in position the notches or slots 43 will face in the same direction and be in alignment with each other.

The chuck 13 is provided with circular openings 45 positioned to register with the upwardly extending studs 32, and to fit thereon the upper tapered ends 42 of the studs as-
5 sisting in placing the openings 45 in the chuck 13 over the studs.

The locking device which cooperates with the notched studs comprises a sliding bolt 46 held beneath two overhanging projections 47 of circular bosses 48 mounted on the chuck 13. This bolt is provided along one edge with rack teeth 49 engaged by a pinion 50 carried by a spindle 51 mounted to turn in a bearing 52 formed in the chuck 13. The spindle 51 at its upper end 53 is formed polygonal in shape whereby it may be engaged by a key or wrench to turn the same, to reciprocate the sliding bolt 46. The bolt 46 near one end is provided with a semi-
10 circular notch 54, the notch being substantially the same radius as the diameter of the studs 32. The parts are so arranged that when the bolt 46 is moved to a point which will bring the notch 54 opposite one of the
15 studs 32, the opposite end of the bolt will clear the other stud, as shown in Fig. 1 of the drawing. By turning the spindle 51, the rack and pinion connection 49 and 50, causes the bolt 46 to be reciprocated so that the
20 edge thereof will engage the slots 43 in the studs and thus lock the chuck 13 and the core mounted thereon, to the table 27. In order to insure rigidity of connection the
25 sliding bolt 46 at its opposite ends is pro-
30 vided with bevelled or wedge surfaces 55 and 56 (see Figs. 4 and 7), whereby as the bolt is moved to a locking position, the under surface of the chuck 13 will be forced into close contact with the upper surface of
35 the table 27.

Preferably, the polygonal ends 26 and 53 will be of substantially the same size and shape so that the same key or wrench may be employed to operate the key section of the
40 core and the sliding bolt 46.

It is thought that the operation has been sufficiently described in connection with the foregoing description of the construction, and that further description is unnecessary.

45 It is sufficient to state that by manipulating

the sliding bolt, the chuck 13 and its sup-
50 ported core may be removed and replaced at will and firmly connected to the table 27 or disconnected therefrom.

We claim:

55

1. In combination, a chuck, a core sup-
50 ported thereon, a table or support for the chuck, a stud carried by said table, an open-
55 ing in said chuck through which said stud projects and a locking bolt carried by the chuck for engaging the said stud.

2. In combination, a chuck, a core sup-
50 ported thereon, a table or support for the chuck, a pair of diametrically arranged
55 studs carried by the table, a pair of openings in the chuck through which said studs pro-
ject, and a sliding bolt carried by the chuck engaging said studs.

3. In combination, a chuck, a core sup-
50 ported thereon, a table or support for the chuck, a pair of studs diametrically arranged on said table, notches in one side of said
55 studs, a pair of openings in the chuck through which said studs project, and a slid-
60 ing bolt carried by the chuck arranged to be engaged with the notches in said studs.

4. In combination, a chuck, a core sup-
50 ported thereon, a table or support for the chuck, a notched post carried by the table and projecting through an opening in the
55 chuck, and a sliding bolt having a wedge sur-
60 face carried by the chuck in position to en-
gage the notch in said stud.

5. In combination, a chuck, a core sup-
50 ported thereon, a table or support for the chuck, a pair of notched studs carried by the table and projecting through openings in the
55 chuck, a sliding bolt carried by the chuck, a clearance notch near one end of said
60 bolt for clearing one of the studs so posi-
65 tioned that when brought into clearance po-
70 sition the opposite end of the bolt will clear the other stud.

6. In combination, a chuck, a core sup-
50 ported thereon, a table or support for the chuck, a sliding bolt for connecting the
55 chuck and table or support, and a rack and
60 pinion mechanism for operating said bolt.

PETER DE MATTIA.
BARTHOLD DE MATTIA.
